[57] CLAIM

The ornamental design for a spout or the like, as shown and described.

DESCRIPTION

FIG. 1 is a right side elevational view of a spout or the like embodying our new design, the left side being a mirror image of the right side shown;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a perspective view, as seen from the front, top and left side of FIG. 1.

FIG. 1

*FIG. 2**FIG. 3**FIG. 4**FIG. 5*FIG. 6
